UNITED STATES PATENT OFFICE.

DANIEL JONES, OF BOSTON, MASSACHUSETTS.

SUCKER-ROD FOR PUMPS.

SPECIFICATION forming part of Letters Patent No. 372,804, dated November 8, 1887.

Application filed May 20, 1887. Serial No. 238,668. (No model.)

To all whom it may concern:

Be it known that I, DANIEL JONES, a citizen of the United States, and a resident of Boston, in the county of Suffolk and State of Massachusetts, have invented new and useful Improvements in Sucker-Rods for Pumps, of which the following, taken in connection with the accompanying drawings, is a specification.

This invention relates to improvements in sucker-rods for pumps, and it is an improvement on the United States Letters Patent granted to me February 27, 1883, No. 273,234.

My present invention is carried out as follows, reference being had to the accompanying drawings, wherein—

Figure 1 represents a side elevation of my improved sucker-rod joint, a part of which is shown in section. Fig. 2 represents a central longitudinal section of the same. Figs. 3, 4, 5, and 6 represent cross sections respectively on lines A B, C D, E F, and G H, shown in Fig. 1. Fig. 7 represents a longitudinal section of a modification of the invention.

Similar letters relate to similar parts wherever they occur on the different parts of the drawings.

In my previous patent above mentioned I provided the socket on its inside with prismatic projections, which were forced into the surface of the wooden rod when the latter was driven into the socket, and in so doing the prismatic projections on the interior of the socket caused longitudinal grooves to be cut on the wooden rod, by which the latter was correspondingly weakened and liable to become broken. To avoid this, and for the purpose of securing the socket to its wooden sucker-rod in a strong, simple, and substantial manner, I construct and arrange the parts as follows:

40 a is the wooden sucker-rod, provided with one or more annular grooves, a' a', as shown.

b in Figs. 1 and 2 is the screw-threaded end or shank of the metallic rod-coupling, which is adapted to be screwed into a correspondingly screw-threaded female portion on the next rod-coupling, in the series. In one piece with the shank b, I prefer to make the longitudinally-slotted tube c, having the slits d d, as shown in Figs. 1, 2, 3, 4, and 5. The slotted

50 metal tube c is provided with one or more an-

nular depressions, e e, corresponding in shape with the annular grooves a' a' on the rod a, as shown in Fig. 2.

The object of having the tube c slotted, as shown, is to enable its ends to be spread apart sufficiently to receive the rod a, after which the expanded portions of said tube c are closed around the grooved rod a, as shown in Figs. 1 and 2, causing the annular depressions e e on the tube c to rest in the annular grooves a' a' on rod a. After the rod a has been introduced in tube c and the latter closed around the former, as shown in Figs. 1 and 2, I surround the tube c with the metal locking-tube f, having a series of gluts, pawls, or projections, g g, which are detached on three sides from said tube f, as shown in Fig. 1, and connected to the tube f in their upper ends only, as shown. Said gluts g are preferably made of increased thickness at their free ends, so that when they are pressed inward into the annular depressions e e on the split tube c the outside of said gluts shall be even, or nearly so, with the exterior of tube f, as shown in Fig. 4. By this arrangement it will be seen that the ends of the depressed gluts g are made to rest and bear against metallic shoulders on the tube c, and not pressed into the wooden rod a, by which the wear and tear of the wooden rod a is prevented and a most strong and durable joint obtained.

When so desired, the annular depressions e and the interior of tube f and its gluts g may be tinned, and after the parts are put together, as described, I may still further unite them by pouring molten solder or alloy through suitable perforations, h h, (shown in Fig. 1,) made in pipe f, into annular recesses e e, by which the tubes c f and gluts g are still further united together. Heretofore the socket end, where it joins the wooden rod, has been made straight; but this is objectionable, as it is liable to cause breakage of the rod at or near the place where it abuts against the metal socket or tube, and to prevent such breakage I make on the end of tube f a pair of diametrically-opposed ears, i i, by which the union of the wood and metal parts is materially strengthened both against lateral and torsional strains.

In the modification shown in Fig. 7 I em- 100

ploy independent slotted or divided metal annular rings $e'e'$, adapted to rest in the annular recesses $a'a'$ of the wooden rod a , thus dispensing with the continuous inner tube, c , as shown in Fig. 2. In said modification I make shank b' in one piece with the metal tube f' , that is provided with gluts, pawls, or projections $g'g'$, in the same manner as heretofore described. After the shoulder rings or parts $e'e'$ have been located in the annular grooves $a'a'$ on rod a , I insert the latter in tube f' and depress the gluts $g'g'$, as shown in the left-hand end of Fig. 7. If so desired, the parts that are to be united may be tinned and still further secured together by means of molten solder or alloy poured between and around such parts, as above described.

If so desired, the outer metal sleeve, f , in Figs. 1 and 2 may in some cases be dispensed with and the depressions $e'e$ on the slotted tube c be filled with molten metal or alloy, in the same manner as a wipe joint is made on lead

pipes, or in a similar or equivalent manner, or wound with wire or suitable material.

What I wish to secure by Letters Patent, 25 and claim, is—

In a sucker-rod joint, the wooden rod a , having annular recesses $a'a'$, and the slotted metal tube c , having depressions $e'e$, fitting into grooves $a'a'$, combined with the metal tube f , 30 surrounding the sleeve c , and having gluts or projections $g'g'$, constructed as described, and adapted to be driven or bent in their free ends against the recesses in tube c , as and for the purpose set forth. 35

In testimony whereof I have signed my name to this specification, in the presence of two subscribing witnesses, on this 16th day of May,

A. D. 1887.

DANIEL JONES.
